(57) **CLAIM**

The ornamental design for a cover for electronic equipment cabinet, as shown.

DESCRIPTION

FIG. 1 is an isometric view of the design for a cover for electronic equipment cabinet in accordance with a preferred embodiment of the present invention;

FIG. 2 is a right side view of the cover for electronic equipment cabinet of FIG. 1;

FIG. 3 is a left side view of the cover for electronic equipment cabinet of FIG. 1;

FIG. 4 is a sectional view of the cover for electronic equipment cabinet taken along line 4—4 of FIG. 1;

FIG. 5 is a front view of the cover for electronic equipment cabinet of FIG. 1;

FIG. 6 is an enlarged view of a portion of the cover for electronic equipment cabinet of FIG. 5;

FIG. 7 is enlarged view of another portion of the cover for electronic equipment cabinet of FIG. 5;

FIG. 8 is a rear view of the cover for electronic equipment cabinet of FIG. 1;

FIG. 9 is a top view of the cover for electronic equipment cabinet of FIG. 1; and,

FIG. 10 is a bottom view of the cover for electronic equipment cabinet of FIG. 1.

Broken lines shown in the drawings illustrate portions of the cover for electronic equipment cabinet, and form no part of the claimed design.
